MAIL PACKET

Albert F. Evers, San Francisco, Calif.

Application October 29, 1956, Serial No. 618,838

4 Claims. (Cl. 232—19)

This invention relates to a receptacle for receiving mail that has been inserted through a slot in a door, wall or the like.

The invention has particular utility with home mail slots of the type provided at about waist height or higher in a garage door, house door, or wall of a house. The slot usually has a spring-urged, normally closed metal flap, so that when the mailman makes his delivery, the mail pushes the flap up to permit insertion of the mail through the slot, and then the flap springs back and closes the slot to prevent anyone outside from reaching inside and stealing the mail.

The common failing of such mailboxes has been in the receipt of the mail on the other side of the slot. If the mail is to be prevented from merely falling to the floor and scattering there, some sort of receptacle must be provided to catch it. Heretofore, the normal practice has been to put a cardboard or wooden box underneath the slot, but this arrangement has not proved satisfactory. The mail frequently spilled out of open boxes and fell to the floor anyway, while covered boxes were inconvenient, not only for withdrawing the mail but also because no one could find out whether there was any mail without actually reaching into the box. Also, the boxes tended to catch and hold dirt, to get the mail dirty, and to dirty one's hand in getting the mail.

Another disadvantage of such boxes was that they stood away from the wall and provided a formidable obstruction, particularly when used with a slot through a side-opening garage door. Such boxes have often been struck when the automobile was being backed out, to the damage of the car as well as of the box. In the case of a slot through an overhead door, such a box often hung down too far where one could strike his head against it, if he were not careful; but also, when the door was raised, any mail then in the box tended to fall out.

One object of this invention is to solve these problems by providing a novel bag-type of receptacle to receive the mail. My new receptacle lies substantially flush against the vertical door or wall, whether it is empty or filled with mail, and it is so constructed that it will catch and hold all the mail. Even when the slot is in an overhead type of garage door, my new receptacle will hang down vertically and will retain the mail safely when the door is raised. My new receptacle will catch all the mail from whatever slot arrangement and hold it without providing any significant obstruction, whatever the kind of mail slot.

One important feature of the invention is the provision of a transparent receptacle, through which one can see even from a distance whether the mail has come. Thus, in a city home with a garage door slot, anyone can open the door leading from the house to the garage and can tell in an instant whether the mail has come, without having to go and look or feel inside, as with covered boxes.

Another object of the invention is to provide a mail-receiving receptacle that is inexpensive to manufacture

2

and that can be mounted in place in a few moments by anyone.

Another important object is to make it possible for a bag-type of mail receptacle to receive relatively long, stiff objects, such as books, magazines, and large envelopes, that may be inserted through the slot. This is accomplished by a novel seam structure and bag construction and mounting.

Another object of the invention is to provide a tight closure to bar the entry of dust into the receptacle whether there is mail in the bag or not. The present invention achieves this object by providing a novel pocket spring which goes into the receptacle and urges the opposite sides away from each other, holding the open flap snugly closed but yielding readily to the entry of one's hand for withdrawing mail.

Another object of the invention is to provide a structure for causing all the mail to fall down below the withdrawal flap and not work its way out of the withdrawal flap and onto the floor. This important object is achieved by a novel overlap structure in which an upper guide flap extends down below and inside of the withdrawal opening. This flap guides the mail down into the main pocket of the receptacle, well below the slot, while the pocket itself extends down far enough so that the entry guard flap does not interfere with removal of the mail through the withdrawal opening.

In general, the receptacle of this invention comprises a transparent plastic bag through which one can clearly see whether there is mail inside. The bag is composed of three main pieces of plastic—(1) a rear wall whose upper edge only is secured to the door or wall below the mail slot; (2) a front wall or flap whose bottom and side edges are seamed to the rear wall to form a pocket 35 therebetween which extends from a bottom seam up to an upper horizontal edge well below the mail slot, which is not joined to the bag and provides the withdrawal opening through which one can reach his hand to pick up the mail; (3) a guard or upper flap whose upper edge 40 is secured to the door or wall above the mail insertion slot and which extends over the slot and down below the withdrawal opening, its lower portion being positioned in between the front and rear walls. An important feature of the invention is the use of a pocket spring comprising 45 spring wire filament shaped to provide a central portion between two side-arms that normally diverge widely from each other; when inserted into the bag the side-arms are restrained by the pocket to a substantially vertical position and provide a strong outward pressure that holds the bag flat and keeps the withdrawal opening closed except when one reaches his hand into it.

Other objects and advantages of the invention will appear from the following description of a preferred embodiment thereof, given in accordance with 35 U. S. C. 55 112.

In the drawings:

Fig. 1 is a perspective view from inside a garage, showing a garage door of the overhead type having a mail slot therethrough to which a mail receiving receptacle embodying the present invention has been applied. The door has been opened partway to show how the receptacle hangs vertically at all times.

Fig. 2 is a fragmentary view in rear elevation on an enlarged scale of the portion of the door carrying the mail slot and the receptacle shown in Fig. 1, with the garage door in its truly vertical position and with mail in the bottom of the receptacle.

Fig. 3 is a view in horizontal section taken along the line 3—3 in Fig. 2, with the thickness of the flaps and their spacing apart somewhat exaggerated to show them more clearly.

Fig. 4 is a view similar to Fig. 3, taken along the line 4-4 of Fig. 2.

Fig. 5 is a view in side elevation and in vertical section, taken along the line 5-5 in Fig. 2.

Fig. 6 is a fragmentary view of the upper portion of Fig. 5, showing a person's hand reaching in and withdrawing mail from the pocket.

Fig. 7 is a view in side elevation and partly in section, of the overhead-type garage door raised to its horizontal position, showing how the bag hangs vertically 10 even when the door is horizontal.

Fig. 8 is a view in elevation and partly in section, showing mail being inserted through the slot into the bag, stiff objects in the mail pushing the bag outwardly, while the guard flap guides the mail down into the 15 pocket instead of permitting it to fall on the floor.

Fig. 9 is a view in front elevation of the pocket spring withdrawn from the pocket.

Fig. 1 shows a garage 10 with an overhead type of garage door 11 mounted for swinging movement on a carriage 12 with return and holding springs 13. The invention is equally applicable to garage doors which open from the side and where, in fact, fewer problems are presented so far as the field of the present invention is concerned, the overhead type of door being shown here purely as an example and in order to illustrate how the present invention solves the problem of catching mail behind a mail slot in such a door.

Through the door 11 is a mail slot 14 having a slotted rear plate 15, (see Fig. 2), a slotted front plate 16, (see Fig. 5), and a spring-urged cover member or flap 17 which normally closes the slot 14 after the mail 18 has been inserted, to prevent anyone from withdrawing the mail from the outside through the slot 14. The slot 14 is conventional and is included only to explain the environment of the invention.

The invention itself comprises a plastic receptacle or bag 20 which is made up principally of four main elements; a rear wall 21, a front wall or flap 22, a guard or guide flap 23, and a pocket spring 24. These four elements are combined in a novel manner to achieve the objects of the invention, and the bag 20 is mounted on the door 11 in a particular relation to the mail slot 14 which is shown particularly well in Figs. 2 and 8.

The rear wall 21, front wall 22, and guard flap 23 are preferably all made from a strong plastic material such as window-clear vinyl plastic. Various thicknesses are usable but a relatively thin stock such as 0.003" thick has produced very satisfactory results and is generally preferred. The seams may be made by sewing, fusing, cementing, stapling, etc. Sewing may give additional strength and is preferred for many applications, although not the only way to achieve the results of this invention.

The rear wall 21 has a reinforced upper horizontal edge 25 secured to the door 11, preferably by thumb-tacks 26, just below the mail slot 14 and hangs down substantially vertically at all times. It hangs flat along the door 11 when the door is in its vertical or closed position shown in Fig. 5; it hangs free, from the thumb-tacks 26, when the door is in its horizontal position shown in Fig. 7.

The front flap 22 may be an integral piece of the rear wall 21, folded over and seamed along the side edge 27, or it may be a separate piece seamed to the wall 21 also at the lower edge 28. Thus, the front wall 22 and rear wall 21 form a pocket 30 with an open end 31 adjacent the upper edge 32 of the front flap 22, parallel to the bottom edge 28 and preferably about two-thirds of the way up from the bottom 28 to the mail slot 14. This upper edge 32 is preferably reinforced to provide additional strength, since it is subjected to wear by the insertion of hands and withdrawal of mail.

The guard flap 23 is also a flat rectangular piece of plastic, preferably of the same kind of material as the 75

walls 21 and 22. Its reinforced upper edge 33 may be secured by thumb-tacks 34 or other convenient means to the door 11 above the mail slot 14, and the flap 23 therefore hangs down over the slot 14. It extends down in between the rear wall 21 and front flap 22 with its lower edge 35 preferably lying about two or three inches below the upper edge 32 of the front flap 22. This relationship is an important feature of the invention, because it insures that all the mail dropped in through the slot 14 will fall into the pocket 30 below the withdrawal opening 31 at the upper edge 32 of the front flap 22 and cannot be pushed out onto the garage floor.

A portion 36 at each side of the guard flap 23 is seamed to the rear wall 21, the overlap portion 37 actually being sandwiched between the front flap 22 and the rear wall 21. The seam 36 extends up above the withdrawal opening 31 but ends several inches below the mail slot 14. From there on the side edges 38 of the guard flap 23 are free. This means that, as shown in Fig. 8, stiff objects 18 can be inserted through the mail slot 14; they will temporarily force the guard flap 23 further away from the door 11 but will not tear the seams 36 between it and the rear wall 21, due to the slack space at 38. Then, after the object is dropped, it is guided down by the guard flap overlap portions 37 into the bottom of the pocket 30. (See Fig. 2.)

Within the pocket 30 of the receptacle 20 is the spring member 24. Preferably, this is made of steel wire of about 0.073" diameter, though other sizes may be used. 30 This wire 24 is formed into the shape shown in Fig. 9, with a central bottom edge portion 40, which is substantially straight before insertion into the pocket 30, and a pair of widely divergent side edges 41 and 42 which extend out at an angle of approximately 65° with 35 respect to the horizontal bottom edge 40. This wire 24 is inserted into the pocket 30 between the front and rear walls 22 and 21 between the rear wall 21 and the guard flap 23. When inserted, the side edges 41 and 42 are straightened out, since the width of the spring's lower edge 40 is substantially that of the lower edge 28 of the pocket 30, within about 1/2". This forcing in of the upper ends of the spring 24 results in the exertion of a strong spring pressure to spread the bag out flat. The result is that the upper edge 32 of the front flap 22 is retained in the closed position, where no dust can get into the pocket 30. Note that, since it is a spring, it will yield readily to insertion of one's hand into the pocket 30 to withdraw the mail 18.

Installation of the bag 20 is very simple. It is sold, of course, as a unit, with the spring 24 inserted in the pocket 30 and with the three flaps or walls 21, 22, and 23, already sewn or otherwise seamed. Installation may be accomplished with any desired securing device, such as six thumb-tacks, three tacks 26 being used to fasten 50 the top edge 25 of the rear flap 23 just below the mail slot 14 and three tacks 34 being used to fasten the top edge 33 of the guard flap 23 just above the mail slot 14.

With the receptacle 20 in position, its use is simple. As shown in Fig. 8, the postman inserts the mail 18 through the slot 14 and this results in temporarily forcing the guard flap 23 out away from the slot 14 and pushes the receptacle 20 away from the door 11, and also pushes the flap 23 away from the rear wall 21. After it has been inserted far enough to pass through the slot 14, the mail 18 falls by gravity down into the pocket 30, below the overlap portion 37 of the guard flap, and, due to the spring 24 and to the weight of the mail 18, the shape shown in Fig. 5 is automatically resumed. When one wishes to withdraw the mail, he simply reaches his hand 55 through the pocket opening 31 between the front flap upper edge 32 and the guard flap 23 and reaches down into the pocket 30, picks up the mail 18 and withdraws it. After he has taken the mail out, the spring 24 automatically closes the opening 31 again so that dust is kept out of the device. The mail cannot work itself out of the

pocket 30 due to the overlap portion 37 of the guide flap 23 and is carried vertically, no matter what the position of the door 11.

To those skilled in the art to which this invention relates, many changes in construction and widely differing embodiments and applications of the invention will suggest themselves without departing from the spirit and scope of the invention. The disclosures and the description herein are purely illustrative and are not intended to be in any sense limiting.

I claim:

1. A receptacle adapted to be secured to a partition having a mail slot therethrough, for receipt of and retention of mail inserted through said slot, comprising a flexible bag having a rear wall with its upper edge adapted to be secured to said partition below and closely adjacent to said slot, a front wall shorter than said rear wall and seamed to said rear wall along the side and bottom edges to form a pocket open along the upper edge of said front wall, and a guide flap with its upper edge extending higher than the upper edge of said rear wall and adapted to be secured to said partition above said slot, said guide flap extending down below said upper edge of said front wall and between said front and rear walls; and a pocket spring comprising a central portion and divergent side arms, fitting in said pocket with its central portion overlying said bottom edge and its side arms forced inwardly and parallel to each other by the seamed side edges, for holding said pocket taut and closing it against dust while yielding to permit withdrawal of the mail therefrom.

2. A receptacle adapted to be secured to a door having a mail slot therethrough for receipt and retention of mail inserted through said slot, comprising a flexible transparent plastic bag having a rear wall with its upper edge adapted to be secured to said door below and closely adjacent to said slot, a front wall shorter than said rear wall and seamed to said rear wall along the side and bottom edges to form a pocket with the upper edge of said front wall unseamed to provide an opening for withdrawal of mail from said pocket, and a guide flap with its upper edge extending higher than the upper edge of said rear wall and adapted to be secured to said door above said slot, said guide flap extending down over said slot and below said upper edge of said front wall and between said front and rear walls to provide an overlap portion having its side edges seamed to said rear wall, the portion of said guide flap above said overlap portion also having its side edges seamed to said rear wall up to a point several inches below the upper edge of said rear wall and

being unseamed thereabove; and a pocket spring comprising a central portion substantially the width of said pocket and divergent side arms, fitting in said pocket with its central portion above and adjacent said bottom edge and the side arms held generally parallel to each other by the seamed side edges, for holding said pocket taut and closing it against dust while yielding to permit withdrawal of the mail therefrom.

3. A receptacle adapted to be secured to a partition having a mail slot therethrough, for receipt of and retention of mail inserted through said slot, comprising a flexible bag having a rear wall with its upper edge adapted to be secured to said partition below and closely adjacent to said slot, a front wall shorter than said rear wall and joined to said rear wall along the side and bottom edges to form a pocket, open along the upper edge of said front wall, and a guide flap with its upper edge extending higher than the upper edge of said rear wall and adapted to be secured to said partition above said slot, said guide flap extending down below said upper edge of said front wall and between said front and rear walls with lower portions of its side edges joined to said rear wall; and spring means fitting in said pocket for holding said pocket taut and closing it against dust while yielding to permit withdrawal of the mail therefrom.

4. A receptacle for receipt of and retention of mail, comprising a transparent flexible plastic bag having a rear wall, a front wall shorter than said rear wall and seamed to said rear wall along the side and bottom edges to form a pocket, and a guide flap with its upper edge extending higher than the upper edge of said rear wall, said guide flap extending down below said upper edge of said front wall and between said front and rear walls, the side edges of the guide flap that lie below the upper edge of said front wall being seamed to said rear wall; and spring means for holding said pocket taut and closing it against dust while yielding to permit withdrawal of the mail therefrom.
